UNITED STATES PATENT OFFICE

LOUIS J. WICK, OF HIGHLAND, ILLINOIS, ASSIGNOR TO WICKS PIPE ORGAN CO., OF HIGHLAND, ILLINOIS, A CORPORATION OF ILLINOIS

SWITCH MECHANISM

Application filed July 28, 1928. Serial No. 295,940.

My present invention relates to a switch mechanism, and more particularly to a unitary structure used as a relay unit in electrically operated pipe organs.

The main object of this invention is to provide a switch mechanism comprising contact means which operates with a wiping or brushing contact and keeps the contact surfaces clean and free from corrosion and deposits. Another object is to provide such a mechanism comprising a swingable contact bar and resilient contact elements some of which are in constant engagement with said bar, and the mechanism being arranged to produce a wiping contact of said bar on said elements. A further object is to provide a switch mechanism comprising resilient contact elements and rotatable means with a contact member thereon for wipingly engaging said elements and provide electric connection therebetween, and to have said member actuated by an electro-magnet with an armature which has direct connection with said rotatable means. Still another object is to provide such a mechanism which comprises a plural number or series of positive and negative contact elements all electrically connected by means of a contact member supported on a transverse member and operated by an electro-magnet which has its armature directly connected to means on said transverse member for turning it and swinging said contact member to provide a wiping contact therewith on all of said elements.

These objects and other objects and advantages are attained with this invention, as will become apparent from the following description, taken in connection with the accompanying drawings, forming a part of this application.

In the drawings:

Fig. 1 is a plan view of my improved switch mechanism, showing its particular adaptation for use in a set of similar units as employed in a pipe organ;

Fig. 2 is a side elevation of my unitary switch mechanism;

Figs. 3 and 4 are front and rear elevations thereof, respectively;

Fig. 5 is a vertical sectional view, taken on

line 5—5 of Fig. 3, but the positive contact elements being omitted to better illustrate the wiping action of the contact bar on the negative ones;

Figs. 6 and 7 are sectional views similar to that of Fig. 5, illustrating the action of the electro-magnet and its armature in swinging the contact bar to engage it with the negative contact elements and produce its wiping contact movement over said elements; and

Fig. 8 is an enlarged detail section, taken on line 8—8 of Fig. 6.

The drawings illustrate my invention in its preferred form, showing the improved unitary switch mechanism, which is especially devised and adapted for use in an electrically operated pipe organ and as one of the relay units which are arranged as a set or group of parallel units, as indicated in Fig. 1; and each unit contains a plural number or gang of positive and negative contact elements, the positive elements being connected to the ground wire, while the negative elements are connectable with suitable wires (not shown) to the gang switches which operate the tonal units of the organ, and these positive and negative contact elements of a unit being electrically connected by a swingable contact bar. Each unit comprises a supporting base 10 upon which the other parts are mounted, and it is provided with holes for receiving suitable fastening elements to mount it in position on a member 11 of the organ.

The contact elements are made of resilient metal, preferably in the form of wires, and are supported on the base 10 by the use of bars or members 12 of insulating material, like wood, which are secured with suitable fastening elements in spaced relation on said base. Each member 12 has grooves or channels 13, 90 in its lower side or face, wherein are mounted the negative contact elements 14 and the positive contact elements 15, the latter having the front contact ends 15' curved upwards, and all being retained in said grooves by fibre or insulating means 16, as best indicated in Fig. 7. These negative elements 14 have their rear ends 18 extended through and above member 12 and are there curved or arranged to have wires attached thereto for connection

to the gang switches for operating the tonal units of the organ; while elements 15 have their ends 19 extended through and above said member 12 and bent over onto a ground wire 20 which extends across the several units in the group, as indicated in Fig. 1, said ends 19 being preferably secured to said ground wire 20 with solder 21 to provide a positive connection.

10 A contact member or bar 22 is provided to swingably extend across the front ends of said contact elements on the several members 12 mounted on the one base 10, and this bar 22 is preferably mounted longitudinally of a roller 5 or rotary member 23 which is preferably made of wood and is pivoted eccentrically at its ends with pivot pins 24 journaled in bracket plates 25 arising from the sides of base 10. A forked member or arm 26 of metal has a narrow end 15 or stem 26' engaged or mounted in roller 23, and extends from the cylindrical surface of said roller for turning it on its pivot pins to swing said bar 22 into engagement with the front ends of the negative contact elements 14, 20 while the curved front ends 15' of the positive contact elements 15 constantly engage and 25 bear against said bar due to their curvature and resiliency, as best indicated in Fig. 2.

The electro-magnet means for engaging 30 arm 26 and directly actuating roller 23 and bar 22 comprising a bracket 27 having a foot 28 adjustably mounted, by means of slots 29 and screws 30, between the members 12 on base 10. An electro-magnet 31 is secured to 35 the upper end of bracket 27 and an armature 32 is pivoted with a pin 33 on the bracket and has a curved part or arm 34 which is movable across the end face 35 of the core 36 of the magnet. Cushioning means 37 and 38 is preferably also provided on core 36 and on a post 39 adjustably mounted on base 10. A pin 40 on the side of the armature engages in the forks of arm 26 to directly actuate the roller and bar and produce the wiping contact between this bar 22 and the positive and the negative contact elements 15 and 14; while a spring 41 is attached to the armature and is adjustably mounted on the bracket by means of a post 42 attached to the spring and to the bracket and being readily bendable to suitably stress the spring thus providing adjustable resilient means for retracting the armature and the arm and thereby the contact bar 22 from the negative contact elements 14.

35 What I claim as my invention and desire to secure by Letters Patent is:

1. In a switch mechanism, parallel contact elements, a roller of insulating material, a contact bar mounted longitudinally of said roller and extending from its surface for swingingly engaging said elements to provide a wiping contact, and curved portions on some of said elements to continuously engage said contact bar during its swing, while the other ones of said elements are straight

and become engaged by said bar upon the rotation of said roller and the swinging of said bar.

2. A unitary switch mechanism comprising a base, flexible contact elements and insulating means for spacing them parallel on said base, and a contact bar and means for swingingly mounting it on said base to provide a wiping contact between it and said elements, some of said elements having curved front portions for continuously engaging said bar, while others are straight and become engaged by said bar while it is being swung.

3. A unitary switch mechanism comprising a base, flexible contact elements, insulating blocks on the base and having grooves in the lower face wherein said elements are mounted, each element extending with one end through its block and some of these elements having this end bent over and having a curved portion at the opposite end, a contact bar extending over said elements and being in constant engagement with said curved portions, and means on said base for operating said bar to provide a wiping contact between it and said elements.

4. A unitary switch mechanism comprising a base, flexible contact elements, brackets on said base, a wooden roller pivoted in said brackets and a contact bar thereon which is in engagement with some of said elements and engages the other elements when the bar and member are swung on the pivots, an arm partly secured in and partly extending from said roller, and an electro-magnet and armature and means on the armature to engage and to operate said arm and produce a wiping contact between said bar and said elements.

5. A unitary switch mechanism comprising a base, brackets on said base, a member swingable on said base, a contact bar carried on said member, resilient contact elements on said base some of which are in constant engagement with said bar and others are engaged by the bar when it is swung, a forked arm extending from said member, an electro-magnet and a pivotally mounted armature having a pin to engage in said fork and swing said arm for moving said bar along all of said elements, and spring means to retract said armature and bar.

6. A unitary switch mechanism comprising a base, insulating means with parallel grooves mounted on said base, contact elements mounted in said grooves and some having curved portions, bracket means on said base, and a member pivoted therein, a contact bar on said member for constantly engaging said curved portions, an electro-magnet and pivotally mounted armature mounted on said base, engaging means on said armature and member for turning the member and moving said bar into contact with certain of said elements and move it along all of said elements, and a spring and readily adjustable means for

mounting it on said base for retracting said armature and bar.

7. A unitary switch mechanism comprising a base, insulating means provided with parallel grooves mounted on said base, contact elements mounted in said grooves and some having curved portions at one end and upturned portions at the other, bracket means on said base and a roller pivoted therein, a contact bar mounted in said roller for constantly engaging said curved portions, an electro-magnet and pivoted armature mounted on said base, an arm having one end secured in said roller, pin means extending from said armature and engaging said arm for turning said roller and moving said bar into contact with the remaining ones of said contact elements and to move it with a wiping contact over all of said elements, and a spring and readily adjustable means for mounting it on said base for retracting said armature and bar.

In testimony whereof I have signed my name to this specification.

LOUIS J. WICK.
